UNITED STATES PATENT OFFICE

150,277

DESIGN FOR A MUSIC BOX

Eric Wedemeyer, Floral Park, N. Y.

Application November 27, 1946, Serial No. 135,136

Term of patent 7 years

(Cl. D56—1)

To all whom it may concern:

Be it known that I, Eric Wedemeyer, citizen of the United States, residing at Floral Park, in the county of Nassau and State of New York, have invented a new, original, and ornamental Design for a Music Box, of which the following is a specification, reference being had to the accompanying drawing, forming part thereof.

Fig. 1 is a front elevational view of a music box showing my new design;

Fig. 2 is a side elevational view;

Fig. 3 is a top plan view; and

Fig. 4 is a side perspective view thereof showing the music box as it appears when in open position.

I claim:

The ornamental design for a music box, substantially as shown and described.

ERIC WEDEMEYER.
